(57) **CLAIM**

The ornamental design for a telematic camera, as shown and described.

DESCRIPTION

FIG. 1 is a perspective view of a first embodiment of a telematic camera;

FIG. 2 is a frontside view of the first embodiment of the telematic camera;

FIG. 3 is a backside view of the first embodiment of the telematic camera;

FIG. 4 is a right side view of the first embodiment of the telematic camera;

FIG. 5 is a left side view of the first embodiment of the telematic camera;

FIG. 6 is a top view of the first embodiment of the telematic camera;

FIG. 7 is a bottom view of the first embodiment of the telematic camera;

FIG. 8 is a perspective view of a second embodiment of a telematic camera;

FIG. 9 is a frontside view of the second embodiment of the telematic camera;

FIG. 10 is a backside view of the second embodiment of the telematic camera;

FIG. 11 is a right side view of the second embodiment of the telematic camera;

FIG. 12 is a left side view of the second embodiment of the telematic camera;

FIG. 13 is a top view of the second embodiment of the telematic camera; and,

FIG. 14 is a bottom view of the second embodiment of the telematic camera.

The dashed lines in the drawings depict portions of the article that form no part of the claimed design.

1 Claim, 14 Drawing Sheets
